(57) **CLAIM**

The ornamental design for a bed, as shown and described.

DESCRIPTION

FIG. 1 is a left front perspective view of a bed showing my new design;

FIG. 2 is a side elevational view, the opposite side being a mirror image thereof;

FIG. 3 is a front elevational view thereof; and,

FIG. 4 is a perspective view of the inside of the footboard.

The broken lines showing the bed rails are for illustrative purposes only and form no part of the claimed design.
